(57) **CLAIM**

The ornamental design for an eye brow and eye lash grooming tool, as shown and described.

DESCRIPTION

FIG. 1 is a perspective view showing the top, rear and left side of an eye brow and eye lash grooming tool which forms my design, the broken lines illustrating portions of a pick handle in this and other figures being for environmental purposes only and forming no part of my design;

FIG. 2 is a top plan view thereof;

FIG. 3 is a left side elevational view thereof, this view and the opposite right side elevational view being identical;

FIG. 4 is a front elevational view thereof; and,

FIG. 5 is a bottom plan view thereof.
